CLAIM

The ornamental design for a toothpick, as shown and described.

DESCRIPTION

FIG. 1 is a top and left side perspective view of the toothpick, showing my design.

FIG. 2 is a view of the toothpick from the front, in accordance with the present invention.

FIG. 3 is a top view of the toothpick, in accordance with the present invention.

In accordance with the present invention, the bottom view of the toothpick is a mirror image of the top view.

FIG. 4 is a view of the toothpick from the rear, in accordance with the present invention; and,

FIG. 5 right side view of the toothpick, in accordance with the present invention.

In accordance with the present invention, the left side view of the toothpick is a mirror image of the right side view.
